UNITED STATES PATENT OFFICE

2,106,721

IGNITION BREAKER

Carl V. Chermendy, Chicago, Ill., assignor to
Frieda Chermendy, Chicago, Ill.

Application June 17, 1935, Serial No. 36,896

7 Claims. (CL 206—36)

This invention relates in general to a circuit breaker and has more particular reference to the ignition breakers commonly used in automobiles.

One of the objectionable features in setting and adjusting the contact points of the circuit breakers now commonly employed in automobiles is that it is almost impossible to set or to maintain the breaker points in alignment due to the fact that the sparks occur between two small flat 5 circular discs, so that if one disc is slightly inclined to the other or if the discs are not in axial alignment, the sparking will occur between the closest surfaces, resulting in uneven wear, pitting and the breaker soon becomes unduly 10 noisy, and inefficient.

The present invention provides a different type of breaker which may be substituted for the breaker arms and fixed breaker points in the present type of equipment and thereby used as a 15 replacement therefor.

A further object of the invention is in the provision of an ignition breaker having an insulating holder in which there is a common bore for the fixed and movable contacts insuring that the contact faces be held in alignment, thereby eliminating 20 wear and pitting of the surfaces, and eliminating noise. This breaker also prevents inefficient or inaccurate setting, installation and adjustment of the points, thereby resulting in greater 25 length of service and a better and more continuous spark because of the alignment and flat engagement of the contact element.

Other objects of the invention will appear hereinafter, the accompanying drawing illustrating a 30 preferred embodiment of the invention.

In the drawing, Fig. 1 is a plan view with one of the breakers in section, of an ignition breaker as now commonly used in automobiles;

Fig. 2 is a modification of one of the breakers; 35 Fig. 3 shows a modification of a closed type of breaker;

Fig. 4 is a view of a breaker similar to that shown in Fig. 3 with a different type of holding spring; and

Fig. 5 shows still another modification of a circuit breaker of this type.

In circuit breakers of the type now used in automobiles, a movable metal breaker arm is mounted upon a fixed pivot pin at one end of the 40 arm and carries a breaker contact at the other end which makes and breaks an electric circuit with an adjustable fixed contact separate from the breaker arm. In the present invention the fixed and movable contact members are mounted 45 within a fibrous or insulating holder which may

be substituted for the breaker arm now commonly employed and adjustably set in position so that the movable contact member is operated by the same breaker cam but is always held in fixed alignment with the fixed breaker member regardless of the variation of adjustment of the breaker itself with respect to its distance from the breaker cam.

Referring now more particularly to the drawing, ignition breakers of this type are usually 10 mounted in a housing 10 having a central rotating shaft 11 upon which a breaker cam 12 is secured. In the housing is a plate 13 to which an adjustable plate 14 is pivoted and these plates are usually adjustable in the housing and the 15 plate 14 has a set screw 15 and an adjustment screw 16 for varying and holding it in position on the plate 13.

The ignition breaker of this invention is applied to a mounting structure as described, by 20 means of upright bearing pins 17 and 18 but instead of an ignition breaker arm mounted for rocking movement by engagement with the cam 12, the present invention comprises a relatively 25 fixed holder 20 of insulating material such as fibre, bakelite, and the like, which has an opening 21 to fit the bearing pin 17 or 18 of an ordinary insulation and also an enlarged opening 22 for receiving an adjustment or set screw 23 by means of which the holder may be secured in 30 any set position on its supporting plate with respect to the breaker cam.

In the breaker shown by Fig. 1, there is a transverse bore 24 through the holder having an enlargement 25 at one end for seating a spring 35 26, and a slot 27 intersecting the bore and providing axially aligned portions for receiving a relatively fixed contact member 28 in the outer side of the holder and a relatively movable contact member 29 in the inner side of the holder 40 having an enlarged head for engaging one end of the spring 26 so that the spring which engages the bottom of the recess 25 at its other end tends to hold the engagement head in contact with the cam 12. The relatively fixed member 28 in 45 this form and also in Fig. 2 is supported at its outer end by a flat spring 38 which engages a projection 31 at the outer end of the contact member 28 so that when the inner or contact end of the member 28 is engaged by the inner end of the movable member 29, it will yield slightly to take up any excess movement which may be imparted by the cam.

In the form shown by Fig. 2, the spring for the movable member 29 is replaced by a flat spring 55

33 which has one end inserted in a slot 34 in the holder 28, and the other end extends over the contact end of the movable member 28.

To complete an ignition circuit, conductors 35 have suitable terminals 36 to be engaged and held by fastening nuts 37 threaded on the movable members 28 and accessible in the slots 27, and the movable members 28 are connected by springs 38 to a holding screw 39 which also constitutes a binding screw for a connector strap 39 extending between the opposite breakers and having an intermediate tab 40 for connecting it by means of a screw 41 to the plate 14 and thence to ground.

In the forms shown by Figs. 3 and 4, a breaker block 45 is provided with parallel transverse bores 46 and 47 in which bearing sleeves 48 are tightly inserted or cast so that an adjustable fixed contact 49 may be inserted in one of the bearing sleeves, and a contact member 50 is movable in the other aligned bearing sleeve with end contact surfaces located in a transverse slot 51 intersecting the bore 46. Extending through the bore 47 is an operating bar 52 having a contact head 53 at one end and having a fixed connection with the movable contact member 50 at the other end, comprising a metal plate 53 which causes them to be moved in unison. A curved tension spring 54 bears at one end upon the plate 53 between the ends thereof and is connected to the holder by a fastening screw 38 as in the construction shown in Fig. 1.

Instead of an outside bearing spring 54, an ignition holder 60 as shown in Fig. 4, may be provided with a recess 61 surrounding the bar 52a so that a spring 62 may be seated therein with one end bearing against the bottom of the recess and the other end bearing against the head 53a.

In the form shown by Fig. 5, a holder 10 has a transversely movable contact member 11 with a spring 12 seated in a recess 13 and tending to press the member against the cam and the outer relatively fixed contact member 14 is secured to a flat spring 15 having coils at the ends for mounting it upon spaced bearing pins 16 so that the fixed contact 14 will give slightly under contact pressure from the movable member 11. A conductor 11 may be electrically connected to either one of the bearing pins 16 for completing the electrical circuit which is broken by the contacts.

In all of these forms it should be understood that the extremities of the fixed and movable members are provided with contact discs of tungsten, platinum, or other suitable material which makes a flat contact surface and resists pitting, in accordance with well known present practice, which constitutes no part of the present invention.

The constructions herein described are intended to be so proportioned that they may be inserted bodily in place of the movable breaker arms and fixed contacts now being used, and also they may be applied and adjusted without the addition of other parts and devices. It is also contemplated that the supporting plates 13 and

14, together with the ignition breakers, may be bodily applied to and removed as a unit from the breaker housings now supplied and used, it being necessary only to make the necessary electrical connections.

I claim:

1. A replacement part for ignition breakers comprising a block of insulating material adapted to be bodily substituted for a pivoted metal circuit breaker arm, means for adjustably setting and holding the block in a fixed position adjacent an ignition breaker operating cam, the block having a continuous bore therethrough, a contact fixed in one end of the bore having a contact face at its inner end, and another contact movable in the bore from the other end by a breaker cam and having its contact face at the inner end and always in fixed alignment to flatly engage that of the fixed contact.

2. An insulating replacement breaker part according to claim 1 in which the block has an opening at one end to engage the usual pivoting screw of an ignition breaker and a slot at a distance from the opening as a center for receiving the binding screw of a metal ignition part for adjustably securing the block in fixed position.

3. A replacement ignition breaker part in accordance with claim 1 in which one contact member is adjustably fixed in the bore, and the other contact member has a spring carried by the block and tending to press the member longitudinally in the bore.

4. In an insulating ignition breaker block according to claim 1, metal sleeves secured at the ends of the bores in which the contacts are mounted, the fixed contact being adjustably threaded in its sleeve.

5. In a replacement part for ignition breakers, a single block of insulating material having a bore therethrough and a slot intersecting the bore intermediate its ends, a contact member adjustably fixed in one end of the bore and projecting into the slot, another contact member movable in the other end of the bore, and the members having end contacts which are located to engage flatly and in alignment in the said slot.

6. A replaceable part in accordance with claim 5 having a spring surrounding the movable member in the holder, bearing at one end against the holder and at the other end against the member, tending to press it outwardly from the bore, and meeting in the slot when it engages the fixed member.

7. A replacement part for ignition breakers comprising a single block of insulating material having parallel bores therethrough, a contact member adjustably fixed in one bore, another contact member movable in the same bore to engage the fixed member, a movable bar extending through the other bore having a head for cam engagement at one end, a connector secured at the other end and to the end of the movable contact member, and spring means tending to hold the fixed and movable contact members together.

CARL V. CHERMENDY.
